UNITED STATES PATENT OFFICE.

GUSTAVE ADOLE KELLER, OF CUSHING, OKLAHOMA, ASSIGNOR OF ONE-HALF TO
JOSEPH V. BAILEY, OF CUSHING, OKLAHOMA.

AIR-TREATING DEVICE.

Application filed January 4, 1923. Serial No. 610,725.

To all whom it may concern:

Be it known that I, GUSTAVE ADOLE KELLER, a citizen of the Republic of Germany, residing at Cushing, in the county of Payne 5 and State of Oklahoma, have invented certain new and useful Improvements in Air-Treating Devices, of which the following is a specification, reference being had to the accompanying drawings.

10 This invention relates to air treating devices for internal combustion engines, and more particularly to a device for treating the air which is admitted to the carburetor thereof.

15 An important object of the invention is to provide a device of this character which simultaneously feeds to the carburetor moistened air and oil laden air.

A further object of the invention is to 20 provide a device of this character wherein the feeding of moistened air is discontinued during those times at which the engine is traveling at low speeds, it having been found that the feeding of moistened air in 25 large quantities to the engine when the same is traveling at low speeds and not highly heated results in a collection of this moisture upon the valves and valve stems with the result that the same become rusty and 30 stick.

A still further object of the invention is to provide a novel and improved means for moistening air for use in an internal combustion engine and for straining from the 35 air any particles of dust or dirt which might be contained therein.

Another object of the invention is to provide a device of this character which may be readily applied to engines of various constructions without materially altering the 40 construction thereof.

An additional object of the invention is to provide a device of this character which is durable and efficient in service and which 45 may be cheaply produced.

These and other objects I attain by the construction and arrangement shown in the accompanying drawings wherein for the purpose of illustration is shown a preferred 50 embodiment of my invention and wherein like reference characters designate like parts throughout.

In the drawings:—

Figure 1 is a side elevation of an internal 55 combustion engine showing apparatus con-

structed in accordance with my invention applied thereto;

Figure 2 is a vertical sectional view through the air moistening device;

Figure 3 is a section on the line 3—3 of 60 Figure 2; and

Figure 4 is a detail sectional view through the connecting conduit.

Referring now more particularly to the drawings, the numeral 10 indicates a casing 65 substantially rectangular in cross section and provided with means, as at 11, whereby it may be secured to the dashboard D of a motor vehicle or to any other suitable support. The casing 10 is provided with a curved upper wall 12 and has extending upwardly from the lower wall thereof approximately centrally of such lower wall a dividing wall 13, the upper end of which is in spaced relation to the curved upper wall 12, forming 70 within the casing a passage 14 having its ends disposed at the bottom of the casing. The bottom wall of the casing has formed therein at one side of the dividing wall 13 an air inlet opening 15 which is covered by a 75 screen 16 to prevent the entrance of large particles of dirt, and at the opposite side of the dividing wall 13 with an outlet opening 17 communicating with a flexible conduit 18.

The numeral 19 designates a water casing 85 which is in communication through its valved inlet 20 with a conduit 21 leading to and communicating with the water jacket W of the engine. This casing is provided along its upper end with a restricted outlet 90 22 in communication throughout its length with the lower end of the casing 10. Arranged within the casing 10 are a pair of shields or strainer members 23 and 24, these shields extending transversely entirely 95 across the width of the casing 10 and being of different lengths. The lower edges of the shields are arranged against the restricted opening 22 of the casing 19 for a purpose presently to appear, and have their upper 100 edges resting against and preferably secured to the dividing wall 13 of the casing 10. Being of different lengths, the upper ends of these strainer members are maintained in spaced relation and the strainer 105 members being flat, are maintained in spaced relation except at the lower ends thereof. The strainer members 23 and 24 have applied thereto a coating of fabric 25, the lower end of which enters the restricted 110

outlet of the casing 19 and the casing 19 is provided with a filling of some material such as absorbent cotton, as indicated at 26. Upon water being admitted to the casing 19, it will be fed along the fabric strips 25 by capillary attraction and moisture will be added to air entering at the inlet 15 and passing through the screens 23 and 24 by contact.

10 The numeral 27 designates a conduit adapted at one end, as at 28, for engagement with the air inlet pipe 29 of the carbureter C, and at its opposite end with an inlet 30 adapted for engagement with the free end 15 of the conduit 18. Adjacent the inlet 30 and within the conduit is arranged a screen 31, and the adjacent end of the air inlet is formed to provide a seat for a ball valve 32 normally held in engagement with such seat by means of a spring 33. Intermediate the screen 31 and the outlet 28, the conduit 27 is provided with a second inlet 34 which is adapted for connection by a flexible conduit 35 and a suitable fitting 36 with a 20 breather outlet B of the engine base.

As will be seen from an inspection of the drawings, the moistened air inlet 30 for the conduit 27 is of less size than the air inlet 34 by means of which the conduit is 30 connected with the engine base. Accordingly at all times during operation of the engine at high speed when a considerable amount of air is being drawn through the inlet of the carbureter, a large amount of air will be drawn from the crank case and a smaller amount from the casing 10, the air from the crank case being laden with gasoline and oil fumes and that from the casing 10 being moistened. When the speed 40 of the engine is lessened to a point when sufficient air can be withdrawn from the crank case without creating therein too great a vacuum, the valve closes and all of the air entering the carbureter is drawn 45 from the case. It is pointed out that since all of the air entering the engine at any time is either drawn from a point at which there can be no dust or drawn through a device which will remove therefrom the dust, the 50 collection of such dust upon the interior of the engine is prevented. To those familiar with the art, it is well known that dust entering the cylinders through the carbureter is one of the major causes of scoring 55 and destruction of the cylinder walls and pistons.

It will be obvious that the construction hereinbefore set forth is capable of some change and modification without materially departing from the spirit of my invention and I accordingly do not limit myself to such specific structure except as hereinafter claimed.

I claim:—

60 1. In an attachment for carbureters, a

conduit having an outlet adapted for engagement with the air inlet pipe of the carbureter and with a pair of inlets, one of which is adapted for engagement with a source of air laden with hydrocarbon and the other of which is adapted for engagement with a source of moistened air, the last named inlet being of smaller size than the first named inlet, and a check valve for the last named inlet opening upon the formation within the conduit of a predetermined vacuum.

2. An air moistening device for internal combustion engines comprising a casing provided in the lower wall thereof with an inlet and an outlet, a water container associated with the casing and having a restricted outlet opening transversely of the casing, a partition extending upwardly from the lower wall of the casing intermediate said inlet and outlet, and moisture distributing devices of different lengths having their lower ends engaging the base of the casing at the restricted outlet of said water container and their upper ends engaged with said partition.

3. In an air moistening device for internal combustion engines, a casing provided in the bottom thereof with a screened inlet and an outlet, a partition wall extending transversely of the casing intermediate said inlet and outlet and extending from the bottom of the casing to a point adjacent the top thereof, a moisture container having communication with said casing through the bottom thereof in the form of a restricted slot and moistening devices each comprising a screen having fabric applied thereto, and of different lengths arranged within said casing and having the lower ends thereof arranged at said slot and the upper ends thereof abutting said partition wall.

4. In an air moistening device for internal combustion engines, a casing provided in the bottom thereof with a screened inlet and an outlet, a partition wall extending transversely of the casing intermediate said inlet and outlet and extending from the bottom of the casing to a point adjacent the top thereof, a moisture container having communication with said casing through the bottom thereof in the form of a restricted slot and moistening devices each comprising a screen having fabric applied thereto and of different lengths arranged within said casing and having the lower ends thereof arranged at said slot and the upper ends thereof abutting said partition wall, said water container being provided with a filling of fibrous material.

In testimony whereof I hereunto affix my signature.

GUSTAVE ADOLF KELLER.
